UNITED STATES PATENT OFFICE.

HENRY C. PFEIL, OF CHICAGO HEIGHTS, ILLINOIS, ASSIGNOR TO AMERICAN MANGANESE STEEL COMPANY, OF CHICAGO, ILLINOIS, A CORPORATION OF MAINE.

CORE FOR MOLDS.

Application filed May 23, 1925. Serial No. 32,254.

This invention relates to a novel construction of core for molds, for instance, sand molds, and has for its object to provide a core construction which will insure accurate 5 sustention of the core in its intended position in those situations where, by reason of the location of a riser or other space in the mold, the sand or mold substance is necessarily omitted to an extent which would otherwise 10 leave the core inadequately supported and therefore subject to displacement which, however slight, is seriously objectionable, particularly when the core is employed for forming the bore of a wheel or other object 15 requiring accurate centering, and still more particularly where the object is being cast of manganese steel, the finishing of which must be accomplished by grinding, which would be both difficult and expensive, and 20 would be prohibitive if relied upon to insure centering of a bore.

It has been proposed to employ wires or other makeshift anchoring means for holding the end of a core away from the riser 25 space or other cut-away portion in the mold, but this method is both time consuming and unreliable. The present invention proceeds upon the principle of equipping the core itself with protruding portions with integral 30 projections or sand-engaging portions located to enter the sand of the mold in directions approximately transverse to that in which the core is liable to tip, and at points on the core sufficiently back from the space 35 or point of weakened support, to firmly embed the core and thus insure its correct up-standing position even though the mold material on one side of the core may be largely removed. The impairment of core support 40 which the present invention seeks to meet usually occurs at one end of the core, for instance, in the cope section of the mold, and the core supporting projections, while located to enter the cope, will extend to the dividing 45 plane of the mold sections so as to leave their impressions as a part of the cope section core print; and in order to insure introduction of the core in the drag section in 50 position to bring the supporting projections into registry with their cope section prints, the lower end of the core, as well as the print which receives it, is suitably deformed from a circular section so that the print will be received in but one position.

In order that the invention may be fully

understood, the preferred embodiment thereof has been illustrated in the accompanying drawing, in which—

Figure 1 is a vertical axial section of a mold minus its pattern and a core embodying the subject-matter of the present invention, the plane of section being through the center of the mold and the pouring runner.

Figure 2 is a plan view of parts shown in Figure 1 with the cope section of the mold 65 removed.

Figure 3 is a detail elevational view of the core as seen from the right of Figures 1 and 2, and on an enlarged scale.

Figure 4 is a top plan view of the core; 70 and

Figure 5 is a side elevation of the core equipped with a section of tubing which is to be left as a liner in the casting.

1 represents the drag section, 2 the cope section, 3 the casting cavity, and 4 the core in a mold which is typical of ordinary foundry practice, for instance, a mold used in casting a wheel. In foundry work of this kind, it is common to connect the pouring 75 runner 5 to the lower portion of the mold cavity, and to leave one or more spaces 6 in which the metal may rise after filling the mold cavity, to vent the mold, carry off scum, and insure a solid casting. When a 80 riser space 6 is located adjacent a core, such as shown at 4, it seriously impairs lateral support for the upper end of a core and leaves the latter subject to displacement by the inrushing metal, with the result that a 85 bore or opening which should accurately correspond with the geometrical center of the casting is so far out of center as to necessitate either discard of the casting or expenditure of an undue amount of time in 90 truing up the bore. In ordinary carbon steel work it is comparatively easy to true a bore in the lathe, and the preferable practice is to use a reduced size of core and dress the opening to bring it to proper size 95 and condition. But this is not practicable in manganese steel work, since the cast object can be tooled and finished only by 100 grinding.

Now, the present invention insures such 105 accuracy in the location of the bore of the casting as will admit of the bore being originally produced with its desired ultimate dimension, and this is accomplished by providing the core 4 with projections such as 110

shown at 7, located to embed themselves in the sand approximately transversely to the direction of tipping tendency, and sufficiently far back from the riser space to insure adequate support and rigid sustention of the core under all displacing influences which it is liable to encounter. Projections 7 are preferably located on the opposite sides of the medial plane of the core from the riser space 6, but not so far to the rear thereof as will reduce their area of connection with the core. Prints for the ends of the core 4 having been accurately located in the drag and cope sections of the mold, and in order to enforce presentation of the core in exact position, that is to say at a predetermined angle of revolution, and insure registry of projections 7 with their imprints, the bottom core print 4 is stepped as shown at 8, or otherwise deformed from circular section so that it will return to the drag section in no other than correct position.

I claim:

1. In a mold, divided by a plane of separation into cope and drag sections, a core crossing the plane of separation and having its respective ends projecting into the two sections, said core being constructed with transverse projections embedded in the material of a mold section and sustaining the core against tipping.
2. In a mold, mold sections, a core supported by its ends in the respective mold sections, one of said mold sections having

adjacent the end of the core a space which 35 impairs support of the core; said core having a portion extending into the mold substance at a point removed from said space.

3. The combination of mold divided by a plane of separation into sections, a core 40 crossing the plane of separation and having its respective ends embedded in said mold sections, one of said sections being recessed adjacent the end of the core which it receives, and said core being provided, at its 45 end which enters the recessed mold section, with projections embedded in the mold substance to one side of the recess and having its other end deformed to insure its introduction into the mold section which receives 50 it at a predetermined angle of revolution.

4. A core for molds, having its ends constructed to enter core prints in a pair of mold sections, one of the ends of the core being formed with transverse projections in 55 position to embed themselves in the walls of the core print which receives said end.

5. A core for molds, having its ends constructed to enter core prints in a pair of mold sections, one of the ends of the core 60 being formed with transverse projections in position to embed themselves in the walls of the core print which receives said end; said projections being both on one side of a medial axial plane of the core. 65

Signed at Chicago Heights, Illinois, this 14th day of May, 1925.

HENRY C. PFEIL.
